UNITED STATES PATENT OFFICE.

WILLIAM V. LAWLOR, OF SAN FRANCISCO, CALIFORNIA.

WASHING-MACHINE.

SPECIFICATION forming part of Letters Patent No. 339,065, dated March 30, 1886.

Application filed March 5, 1885. Serial No. 157,811. (No model.)

To all whom it may concern:

Be it known that I, WILLIAM V. LAWLOR, a resident of San Francisco, State of California, have invented an Improved Washing-
Machine; and I hereby declare the following
5 to be a full, clear, and exact description of the
same, reference being had to the accompany-
ing drawings.

My invention relates to an improved means
10 for washing clothes and other articles by steam
with facility and economy, and with the least
damage and wear to the same.

The following description fully explains
15 the nature of my said invention and the man-
ner in which I proceed to construct, apply,
and operate the same, the accompanying draw-
ings being referred to by figures and letters.

Figure 1 gives a view of the elevation of
20 the machine. Fig. 2 is a plan view showing
the cover removed. Fig. 3 is a view of the
elevation of the revolving cylinder. Fig. 4
is an end view of the same. Fig. 5 is an en-
25 larged view of the internal perforated pipe.
Fig. 6 is a plan view of the same. Fig. 7 is
a view of the perforations in the internal
pipe. Fig. 8 gives a view of the deflecting-
plate in the machine.

Referring to Fig. 1, *a* is the boiler, of which
25 *b* is the cover; *c*, the revolving drum; *d*, the
deflecting-plate above the bottom of the
boiler; *l*, rubber rollers at corners of the open-
ing in the deflecting-plate, and *m* the steam-
30 escape.

Referring to Fig. 2, the handles *f* of the
35 machine and the crank *h* and pivot *g*, attached
to the drum-shaft, are shown, and the perfora-
tion *n* in the circumference of the drum, for
the entrance of steam and the escape of water.

Referring to Fig. 3, the revolving drum *c*,
40 the hinges *i*, for the cover of the drum, and
the bolt *j*, for fastening the same, and the po-
sition in the drum of the perforated pipe *k*
are shown.

Referring to Fig. 4, the perforations *n* in the
45 circumference of the drum are shown.

Referring to Figs. 5, 6, 7, the construction
and arrangement in the drum of the pipe *k*
and its perforations *o* are shown.

Referring to Fig. 8, *d* is the deflecting-
50 plate, to prevent the steam from passing out-
side of the drum, and *d'* the opening in the
plate for the drum to revolve.

As may be seen from the description, my
improved machine is especially adapted for

household use, although it may be employed 55
to equal advantage in washing clothes on a
larger scale. The use of steam instead of
water, as it is applied in my machine in the
process of washing clothes, is a thorough, rap-
id, and economical means of effecting this re- 60
sult.

The machine is simple in construction, and
its operation is as follows: It is made of any
suitable metal, and of a size adapted to plac-
ing upon an ordinary kitchen-stove, for which 65
it may be used as an ordinary boiler, if de-
sired. The stove is the heating apparatus.
The amount of water required in the boiler
for generating steam is held in the space be-
70 low the deflecting-plate. The revolving drum 70
cuts through the opening in the deflecting-
plate, as shown in Fig. 1. The sides and ends
of the opening in the plate are cushioned
75 with rubber, and at the corners of the open-
ing are rubber rollers *l*, Fig. 1, for the drum 75
to act upon. The drum, in which the clothes
are placed, is perforated in its circumference
for the entrance of steam and the escape of
water, and inside of it are pipes perforated
80 and of a peculiar construction, and arranged
in position, as shown at *k*, for the purpose of
properly distributing the steam, Fig. 3. The
perforations in the drum admit steam from
the boiler, as do also the perforations in the
85 pipes, from which it is discharged through
the drum. When clothes are to be washed,
they are put into the drum, the cover of
which is closed and fastened, and the drum
is revolved by the crank until the clothes are
thoroughly steamed and cleansed, a result 90
which is achieved in a short time. If steam
is generated too rapidly, it is allowed to es-
cape by the valve, and when the operation of
washing is completed there is a faucet for the
95 discharge of the water.

Having thus fully described my invention,
what I claim, and desire to secure by Letters
Patent, is—

In a washing-machine, the metallic drum
c, and provided with perforated pipes *k*, at-
100 tached inside, and deflecting-plate *d* and rub-
ber rollers *l*, substantially as described and
set forth.

WILLIAM V. LAWLOR. [L. S.]
